UNITED STATES PATENT OFFICE

HARRY J. WELCH, OF GRAFTON, OHIO

SHAFT SEAL

Application filed February 21, 1931. Serial No. 517,531.

This invention relates to shaft seals. It has to do more particularly with an improved form of seal that is adapted to be utilized in connection with the water pump shaft of an internal combustion motor, although it is not limited in its use to the specific instance noted above and may be employed in other capacities if so desired.

Heretofore much difficulty has been experienced in providing a shaft seal that would be more or less of a "permanent" nature and would operate for the purpose intended without breaking down or leaking. In some instances, the shaft has been surrounded with a packing material that was expanded by means of a packing nut, quite difficult to accurately adjust and maintain in adjustment. The least over-pressure on the material would result in the glazing or hardening thereof and the subsequent destruction of the seal, thus necessitating replacement which is both expensive and troublesome.

More in particular, this invention is directed to a pump shaft assembly that may or may not mount a fan on one end thereof and that includes as a novel part of the combination, a pair of co-operating seal members, each having a wedge or tapered engagement with the other, one of such members being fixed and the other of said members being rotatable with relation thereto and movable axially toward and away therefrom. The movable member, in the preferred form of shaft assembly may be formed as a part of the shaft and is moved thereby into sealing engagement with the first named member. The shaft, in turn, is urged by the resilient pressure of a spring or the like to maintain the engagement between the co-operating members regardless of wear therebetween. If the pump shaft mounts a fan, the "pull" of the fan is also effective to tend to move the shaft axially in the proper direction to effect and maintain the above mentioned "seal".

In addition to the objects that are apparent from a study of the preceding paragraph, it is a further object of this invention to provide a pump shaft assembly including such means as will permit of the continued and efficient operation of such apparatus for the purpose intended without requiring frequent attention to place the parts in adjustment.

Another object of this invention consists in the provision of a pump shaft assembly, per se, that may be manufactured at a relatively low cost and may be readily installed as a replacement for worn out or unsatisfactory types of pump devices, or, on the other hand, may be installed as standard equipment in new motors to thereby provide a leakproof assembly at the outset.

Other objects and advantageous features of this invention will be noted in the accompanying drawing and the following description wherein like figures of reference designate corresponding parts and wherein:

Fig. 1 is a vertical longitudinal section through the preferred form of my pump shaft assembly;

Fig. 2 is a horizontal longitudinal section of the assembly shown in Fig. 1;

Fig. 3 is a detail in section of the resilient means for imparting a thrust to the pump shaft;

Fig. 4 is a modified showing of the shaft assembly.

With reference to the drawing, I have shown in Figs. 1 and 2 the preferred form of my invention as comprising a pump shaft assembly mounted on the water jacket 1 of an internal combustion motor. This assembly comprises a shaft 2 which extends through a shaft opening in the jacket that is desired to be sealed. The primary seal is effected by means of an end plate 3 formed as part of the bracket 4 that rotatably supports the opposing end of the shaft 2 in a bearing 5. In the showing in Fig. 1, a pro-

eller fan 6 is mounted at the end of the shaft for rotation therewith. The opposing end of the shaft lying within the jacket 1 carries an impeller 7 that is also mounted for rotation therewith, the shaft being turned by means of the usual pulley 8 and belt 9 arrangement.

To prevent leakage of water from the water jacket, a tapered bushing 10 of bronze or other suitable material is secured in the end plate 3 and is adapted to encompass a tapered enlargement 11 formed as a part of the shaft 1. The tapered construction of the bushing 10 and enlargement 11 provides for a leak-proof joint. The wedge-like engagement of these two members is maintained at all times, regardless of the amount of wear produced by the frictional engagement of such surfaces, by a means adapted to exert a force on one end of the shaft 2 to bias it toward movement in the direction of the arrow, Fig. 1.

This means comprises a plug 12 that is slidably mounted on the inner end of the shaft 2 and is pressed outwardly by a spring 14, Fig. 3, the movement of such plug being limited by a crosspin 15 riding in an elongated slot 16' in the shaft. The head of the plug is designed to ride against a portion of the cylinder head casting, shown at 16, Fig. 1, which serves as a thrust bearing so that the tension of the spring 14 normally presses the shaft outwardly. Thus, movement of the shaft in the direction indicated would maintain the bearing surfaces in contact to take up wear therebetween and provide a leak-proof joint. As the plug 12 lies within the water jacket the contact surface between the cylinder head casting and the end of the plug will always be lubricated by the water in the jacket.

Fig. 4 shows an alternative arrangement of bushing wherein the numeral 20 indicates a hardened steel tapered bushing that is mounted for rotation with the shaft 2 by being keyed to or pressed thereon and is adapted to bear within the bronze bushing 10, the only difference between this arrangement and the one shown in Fig. 1 residing in the integral nature of the bushing 11 with respect to the shaft 2.

Fig. 4 also shows an alternative arrangement for providing a thrust bearing for the plug 12 that takes the form of a U-shaped strap 23 adapted to be formed as a part of the bracket 4 and is to be utilized where the water jacket 1 is not provided with a portion as at 16 of Fig. 1.

As will be noted, in both forms shown, pressure fittings as at 25 are provided that connect with conduits leading to the bearing surfaces to be lubricated. In Fig. 4 the bearing 10 is shown as being encompassed by a lubricant reservoir 26 concentric with the shaft 2 that communicates with the friction-

ally engaging surfaces by means of conduits 27 formed in the bushing 10.

Although I preferably intend to construct these pump assemblies for installation on the forward end of the water jacket, it will be seen that such may be mounted at other points on the vehicle and may, if desired, be chain driven from the engine cam shaft. However, in the preferred form shown in Fig. 1, the apparatus is adapted to carry the air fan on one end of the shaft and it may be stated at this point that such fan operates as an auxiliary means, in addition to the resilient force of the spring 14, to move the shaft 2 outwardly to thereby effect a leakproof joint between the bushing 10 and enlargement 11. The "grasp" of the blades on the moving column of air flowing thereover during rotation is sufficient to set up a pull on the shaft 2 that aids in producing an efficient leakproof engagement between the sealing surfaces.

A shaft seal of my novel construction is both simple and highly efficient in operation and will remain in operative condition for an indefinite period due to the arrangement of parts wherein the seal members are always biased toward firm efficient co-operation.

It is believed that the sealing action of devices embodying the present invention is largely due to the arrangement of the conical or tapered surfaces. When one of such surfaces is fixed and the other is rotated and when the larger ends of such surfaces are exposed to liquid a pumping action takes place between the two surfaces which causes or tends to cause liquid between the surfaces to flow toward the larger ends of the latter. This action is sufficiently great to overcome any tendency of liquid to flow in the opposite direction and out at the smaller ends of the tapered or conical surfaces and hence the device effectively seals itself against liquid leakage. This pumping action is sufficient in itself in many instances to make it unnecessary to apply spring force to urge the shaft axially and bring the conical surfaces into closer engagement with each other. For example the force of gravity in the case of a vertical-axis shaft or the flowing head of water axially against the impeller may be sufficient without force such as spring pressure to maintain the conical surfaces in liquid sealing cooperation.

It is obvious that modifications and variations in the construction and arrangements of parts of my pump shaft assembly may be made without departing from the spirit of my invention and I do not, therefore, limit myself to the precise details shown and described but claim as my invention all embodiments thereof coming within the scope of the appended claims.

Having thus described my invention, what I claim is:
